UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

DESIGN FOR A RANGE.

SPECIFICATION forming part of Design No. 24,603, dated August 20, 1895.

Application filed November 22, 1894. Serial No. 529,654. Term of patent 7 years.

To all whom it may concern:

Be it known that I, THOMAS I. RANKIN, a citizen of the United States, residing in Philadelphia, Pennsylvania, have invented a new 5 and useful Design for a Portable Range, of which the following is a specification.

My design for a cooking stove is clearly illustrated in the accompanying drawing, which represents the stove in perspective.

10 The essential features of the design are the ornamentation of the base, the oven-door, and fire-door.

The base A of the stove has lugs a, on which are fan-like scrolls. The skirts a' between 15 the legs are each ornamented with a twisted-ribbon scroll inclosing a series of rosettes. In the center of each skirt is an inverted heart-like ornamentation.

The oven-door B has a raised design in the 20 shape of a distorted oval inclosing the name-band. Surrounding this oval are a series of shell-like foliated scrolls.

The fire-door C has an ornamental rosette

surrounded by a flat scroll in keeping with the oven-door. Below the fire-door is a de- 25 sign composed of three fan-like scrolls.

The water-heater D is ornamented in keeping with the fire-door.

I claim—

1. The design for the cooking stove as herein described and shown in the accompanying drawing. 30

2. The design for the base of a cooking stove as herein described and shown.

3. The design for an oven door of a cooking 35 stove as herein described and shown.

4. The design for a fire door as herein described and shown.

In testimony whereof I have signed my name to this specification in the presence of 40 two subscribing witnesses.

THOMAS I. RANKIN.
